United States Patent Office.

R. G. ELDER, OF NEW YORK, N. Y.

Letters Patent No. 99,420, dated February 1, 1870.

IMPROVED HANDLE FOR CHILDREN'S CARRIAGES.

The Schedule referred to in these Letters Patent and making part of the same.

To all whom it may concern:

Be it known that I, R. G. ELDER, of the city, county, and State of New York, have invented a new and improved Handle for Child's Carriage; and I do hereby declare the following to be a full, clear, and exact description thereof, which will enable those skilled in the art to make and use the same, reference being had to the accompanying drawing, forming part of this specification, in which drawing—

Figure 1 is a perspective view of this invention.

Figure 2 is a sectional plan of the same.

Similar letters indicate corresponding parts.

This invention consists in a handle for child's carriage, provided with a top, made of metal, either solid or hollow, in such a manner that a strong and durable article is obtained, the metallic top being so constructed that it can be readily and securely fastened to the shanks of the handle, and that it is not liable to tarnish, or become discolored by contact with the hands, in using the carriage, particularly in hot weather.

The handle-tops for children's carriages, according to the present style, are made of wood, painted and varnished, and said tops are fastened to the shanks of the handles, by boring holes into them, and inserting the shanks. These holes, from the nature of the article, can only be of limited depth, and the tops are liable to split or to come off, and furthermore, the paint or varnish of the wooden top is liable to soil the hands, particularly in hot weather, when the carriage is most used, and, by frequent contact with the hands, such paint or varnish is liable to come off, and the carriage becomes defaced.

All these disadvantages are obviated by my inven-

tion, my handle-top, A, being made of metal, either cast or otherwise, and either solid or hollow, as may be most desirable. I make the same, by preference, of such metal which admits of being plated with silver, so that a fine polish can be given to said handle, and a handle is produced which is not liable to tarnish.

My metallic handle is, by preference, provided with projections a, which are bored out, or otherwise made hollow, to form sockets, for the ends of the shanks B. By these projections the depth of the sockets is increased, and the strength and durability of the handle are materially improved.

My metallic handle-top can be readily connected to the shanks B, so that the handle can be taken apart, for shipping, and firmly put together for use, while the ordinary wooden top must be glued to the shanks, so that it can not be taken apart; and, furthermore, such wooden tops are constantly coming off, much to the annoyance of the owner, and danger to the child, when riding.

My metallic handle-top is not liable to come off, it is strong and durable, it can be made cheap, and it materially improves the durability and appearance of the carriage.

What I claim as new, and desire to secure by Letters Patent, is—

A handle for children's carriages, provided with a metallic top, A, substantially as shown and described.

R. G. ELDER.
